UNITED STATES PATENT OFFICE.

HARRY SWEET, OF BURT LAKE, MICHIGAN.

BERRY-PAIL.

SPECIFICATION forming part of Letters Patent No. 510,723, dated December 12, 1893.

Application filed March 28, 1893. Serial No. 468,015. (No model.)

To all whom it may concern:

Be it known that I, HARRY SWEET, a citizen of the United States, residing at Burt Lake, in the county of Cheboygan, State of Michigan, have invented certain new and useful Improvements in Berry-Pails; and I do hereby declare the following to be a full, clear, and exact description of the invention, such as will enable others skilled in the art to which it appertains to make and use the same.

My invention relates to an improvement in berry-pails.

The object of my invention is to produce a pail specially adapted for use when picking berries, in order that both hands of the wearer may be free to do the picking.

A further object of my invention is to produce a berry-pail into which the berries may be dropped with certainty, even by a careless picker and none of the berries lost by being dropped outside the pail.

A further object of my invention is to prevent the berries, after being once deposited in the pail, from being accidentally spilled out by the movements of the picker.

The invention will first be described in connection with the accompanying drawings, and then pointed out in the claims.

In the drawings—Figure 1 is a perspective view of my improved berry-pail. Fig. 2 is a transverse sectional view of the same.

Referring to the drawings, A is a hollow truncated cylindrical receiver, composed of end pieces 1, preferably of wood, to which is secured a curved sheet 2, preferably of metal, such as tin, the mode of fastening shown in the drawings being by screws 3. This receiver is provided on either side, near its bottom, with a waist belt B composed of two straps 4, one of the straps being provided with a buckle 5 by means of which the belt may be united around the waist of the wearer. A similar belt C, also provided with buckles 6, serves to support the pail from the shoulders.

D, D' are a pair of longitudinal deflectors formed, preferably, integral with the curved sheet 2 and having ends 7 which are soldered or otherwise attached to the deflectors. These deflectors, as will be plain from the drawings, form a hopper-shaped mouth for the receiver, and, at the same time, prevent any berries from accidentally rolling out of the receiver when the pail is swung or jarred by the movements of the picker.

It will be observed that, while the inner 55 edge of the deflector meets and is joined to the top edge of the curved sheet 2, as shown at 8, the inner edge of the deflector D', projects some distance inward to the point 9. Moreover, the curved sheet 2 ends at the point 60 10, as will be seen from Fig. 2. By this construction, the space under the deflector D is cut off from all communication with the berry receptacle, while the space beneath the deflector D' is open to the receiver, thereby 65 permitting the berries to roll upward into said space when the pail is tilted forward accidentally. As the space below the deflector D is cut off from the receiver, the berries may be emptied from the pail when desired by 70 pouring them out over the edge of the deflector D.

Having thus fully described my invention, what I claim, and desire to secure by Letters Patent, is—

75

1. In a berry-picker's pail, the combination, with a receiver, of a deflector on each side of the mouth of the receiver, a waist-belt attached to the receiver near its bottom, and a shoulder-belt attached to the receiver above the waist-belt, substantially as described and for the purpose set forth.

2. In a berry-picker's pail, the combination, with a truncated cylindrical receiver, and a deflector on each side of the mouth of the receiver and formed integral with the sides thereof, of a waist-belt attached to the receiver near its bottom, and a shoulder-belt attached to the receiver above the waist-belt, substantially as described and for the purpose set forth.

3. In a berry-picker's pail, the combination, with a receiver, of a deflector on each side of the mouth of the receiver, one of the deflectors having the space beneath it in communication with the receiver, the space beneath the other deflector being cut off from the receiver, substantially as described and for the purpose set forth.

In testimony whereof I affix my signature in presence of two witnesses.

HARRY SWEET.
